CLAIM

The ornamental design for a combined detachable shelving and display wall, as shown and described.

DESCRIPTION

FIG. 1 is a top, front and side perspective illustration of a combined detachable shelving and display wall, showing my new design, the location of the detachable shelving being shown by way of example. The broken lines of the articles are shown for illustrative purposes only and form no part of the claimed design;

FIG. 2 is a side elevational view thereof, the opposite side being a mirror image; and,

FIG. 3 is a top plan view thereof, the bottom being a mirror image of the top shown.
